UNITED STATES PATENT OFFICE.

JAMES SMITH STOCKMAN, OF SOUTH SHIELDS, ENGLAND.

BUOYANT GARMENT.

1,267,140.

Specification of Letters Patent. Patented May 21, 1918.

Application filed April 23, 1917. Serial No. 164,020.

To all whom it may concern:

Be it known that I, JAMES SMITH STOCKMAN, a subject of the King of England, residing at South Shields, in the county of 5 Durham, England, have invented a Buoyant Garment, of which the following is a specification.

This invention relates to buoyant garments of the kind comprising a coat or 10 waisted or sleeveless jacket provided with independent flexible air-tight bags or chambers extending over the chest or over the chest and back, each having a valve flexible tube whereby it can be inflated so as to 15 render the garment, on emergency, sufficiently buoyant to support a person in water. The object of the present invention is to provide an improved garment of this type which has the added advantage that it can 20 be safely used even though one of the air bags or chambers should happen not to be airtight or to be otherwise unusable.

A buoyant garment in accordance with this invention is of the type above referred 25 to and is characterized in that the waist-coat is provided with two independent flexible air-tight chambers or bags each of substantially crescent-shape and so disposed that, when inflated, the bags fit closely one 30 under each arm of the wearer and partially encircle the arm but not extending substantially over either the chest or back, the center of buoyancy being such that the wearer is supported in an inclined position with his 35 face and chest above the water, or, if either bag happens not to be air-tight, the other can be secured under the chin so as to partially encircle the wearer's neck, means being provided for securing either bag in position around the neck so as to support the 40 head of the wearer above the water.

The drawing illustrates a garment embodying my invention, the garment being partly folded for convenience of illustration.

Referring to the drawing, the garment therein illustrated consists of an external expanding waist-coat or sleeveless jacket having arm holes *a a*. Disposed at each side 50 beneath the arm holes *a a* is a flexible chamber or bag *b* which is secured between the cloth of the jacket and the inner lining thereof by attaching the small rings *c* at the ends of the bags by sewing or otherwise 55 conveniently to the cloth. The flexible bags

b may be of rubber inclosed in casings of cloth or fabric, and are approximately crescent-shaped as shown so that, when inflated, they partially embrace the arms but do not extend substantially over either the chest or back of the wearer. Each bag is provided with a flexible pipe *d* having a non-return valve *e* or a valve which can be readily closed by the wearer of the jacket, said pipes forming the means whereby the bags can be inflated. Loops (not shown) may be provided on the inside of the jacket at each side to receive said pipes. The jacket is fastened by buttons *f* and button holes *g* down the center of the front, and may be provided with pockets *h* at both sides of the front which may be used for holding a flask of brandy or other restorative, or a watertight case or box of compressed food or the like.

In use, the improved garment is intended to be worn in place of the usual waist-coat, the flexible bags *b* being normally deflated. When occasion arises, the two flexible bags can be easily and quickly inflated by the wearer blowing into the pipes *d* attached thereto, and, when inflated, the bags render the jacket sufficiently buoyant to support the wearer in the water. The plaits *j* allow the jacket to expand when the bags *b* are inflated. If it should accidentally happen that one of the bags *b* is not air-tight owing to puncture or other cause, the jacket can be removed and replaced with the other bag around the neck of the wearer by thrusting the head through the adjacent arm hole *a* of the jacket, means such as the tapes *k* or an elastic or adjustable band or the like being provided for each arm hole for securing the jacket around the neck. The inflatable bags *b* are of such capacity that one alone will be sufficient to keep a person's head above water.

In some cases the jacket may be provided with an additional inflatable flexible bag or chamber at the front or at the back, or both, which additional bag or bags will be independent of the bags *b* under the arms and of each other. When a front bag is provided, the jacket may be adapted to fasten down the side, and, if desired, a strap or belt may be provided which can be passed between the legs and fastened at the front and back so as to keep the jacket close against the body of the wearer when in the water.

Having now fully described my said invention what I claim and desire to secure by Letters Patent is:—

A buoyant garment of the character designated, comprising a sleeveless jacket, crescent shaped inflatable bags positioned with their concavities under the arm pits thereof, and between the face cloth and the lining thereof, means for inflating said bags, and 10 plaits in the sides and back portions of the

garment which allow the latter to expand when the bags are inflated.

In testimony whereof I have hereunto set my hand in the presence of two subscribing witnesses.

JAMES SMITH STOCKMAN.
